UNITED STATES PATENT OFFICE.

LYDIA B. KOCH, OF NEW YORK, N. Y., ASSIGNOR TO REINFORCED PAPER BOTTLE CORPORATION, OF NEW YORK, N. Y., A CORPORATION OF DELAWARE.

METHOD OF CONSTRUCTING BOTTLE-RECEPTACLE ELEMENTS.

Application filed November 26, 1923, Serial No. 677,015. Renewed March 2, 1928.

Among the principal objects which the present invention has in view are: To form a bottle receptacle having a substantially cylindrical body and a frusto-conical neck 5 in a single operation; to construct a receptacle of the character set forth from two strips of material, the meeting edges whereof are interleaved in the operation of shaping the receptacle; to reduce the time factor 10 required for the manufacture of said receptacle; and to produce in the completed article, a view opening having a transparent closure member interleaved between the plies of the structure.

15

Drawings.

Figure 1 is a schematic view showing the initial relation of flat sheet blanks from which the receptacle is constructed.

20 Figure 2 is a view showing the receptacle as partially completed.

Figure 3 is a top view of the same.

25 Figure 4 is a vertical section of the same, the section being taken on the line 4-4 in Fig. 3.

Description.

As seen in Figure 1 of the drawings there are two blanks of sheet paper. The blank 30 indicated by the numeral 9 is circular in form constituting a segment of an annular strip. The edges 10 and 11 of the blank 9 are concentric. Adjacent the edge 11 is an area 12 provided with a suitable adhesive. The blank 35 has at suitable intervals, openings 13 so related that when the blank is wound upon itself to form the frusto-conical neck or upper portion of the receptacle, the two openings register. Adhered to the blank 9 over one 40 of the openings 13 is a small patch of transparent material as indicated by the numeral 14.

The blank 15 is an elongated strip, the edges 45 16 and 17 whereof are parallel. The length of the strip 15 at the edge 16 thereof is equal to the length of the edge 11 of the blank 9, and an area 18 of the blank 15 adjacent the edge 16 thereof corresponds in width with the area 12 of the blank 9, and is provided 50 with an adhesive, coextensive with the latter half of the blank 15.

The length of the blank 15 is sufficient in the present disclosure to fold twice about a mandrel to form a cylindrical body of the 55 receptacle, it being desired to construct the

same with two plies of material, said material being preferably a prepared moisture-proof paper.

With the two blanks formed as shown, the areas adjacent the edges 11 and 16 are lapped 60 at one end of the two blanks as shown best in Figure 1 of the drawings. The blanks are then rolled preferably over a suitable shape or mandrel, the gummed areas of the two blanks being forced into juxtaposition 65 and pressed one upon the other.

In the course of the manufacture it will be found that both blanks are wrapped to form a two-ply structure, the free edges of the said blanks registering in the completed 70 structure. The upper edge 10 of the blank 9 will form a contracted opening, while the lower edge 11 of the blank 9 will correspond with the dimension of the edge 16 of the blank 15.

75 It will also be found that the area 18 which is supplied with adhesive, overlaps and is permanently attached to the juxtaposed surface of the blank 9. In other words, the first half of the blank 9 corresponding with the area 12 will be adhesively attached to the juxtaposed surfaces of both halves of the blank 15.

The ends of the blanks 9 and 15 are provided with areas 19 and 20 which are provided with adhesive and are pressed down upon the first layer or ply which has been turned or rolled upon the shape or mandrel.

When the mandrel or other shape is withdrawn it will be found that a bottle-like receptacle having upper and lower parts permanently united has been constructed.

With receptacle elements thus constructed and arranged they are then provided with suitable bottom which is inserted between the side walls of the cylindrical portion formed by the blank 15 and is suitably secured thereon. A top of any suitable character is provided for the receptacle. As these structures form no part of the present invention, illustration and description thereof have been omitted.

Claims:

1. A method of forming body portions of receptacles as characterized comprising shaping sheet blanks, the one rectangular and the other arcuate and then rolling said blanks upon themselves and upon each other simultaneously.

105 2. A method of forming body portions of

receptacles as characterized comprising shaping sheet blanks, the one rectangular and the other arcuate and then rolling said blanks upon themselves and upon each other simultaneously, the juxtaposed edges of said blanks being overlapped and adhesively engaged.

3. A method of forming body portions of receptacles as characterized comprising shaping sheet blanks, the one rectangular and 10 the other arcuate; and then rolling said

blanks upon themselves and upon each other simultaneously, one edge of each blank equaling in length an edge of the other blank and adapted to be overlaid one upon the other, the entire inner surface of the arcuate blank and 15 half of the inner surface of the rectangular blank being adhered fixedly one to the other and simultaneously.
